CLAIM

The ornamental design for a packaging with two columns of six, twelve ounce cups in parallel columns, as shown and described.

DESCRIPTION

FIG. 1 is a top side perspective view of a packaging with two columns of six, twelve ounce cups in parallel columns, showing my new design;

FIG. 2 is a bottom side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
